UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,830, dated March 21, 1882.

Application filed February 11, 1882. Term of patent 3½ years.

To all whom it may concern: -

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A consists centrally of a horizontal rectangular figure, a portion of a star-shaped flower 15 above, and an irregular leaf formation below. On a stem depending from A is the flower B, having pointed petals and spreading corolla, from which projects a similar serrated flower, P. On the same stem is the group C, a small 20 fan-like flower at the fork of two leaf-sprays. Lower on the same stem is D, (shown at top of photograph,) a heart-shaped flower with spreading petals and projecting bud from a. A is set on a stem projecting from E, a bulb-shaped 25 flower, which is carried on a stem forking from a main stem which bears in succession the serrated flowers, with pointed petals and spreading corollas, F G H K L M, the star-shaped flower N, and the open bulb-like flower O, with 30 spreading petals and a blossom-and-leaf spray above. Between these larger flowers on this

stem are various small leaf and blossom forms and small star-like flowers, filling the ground of the design almost completely.

Q is an open bulb-like flower with spreading 35 serrated petals, from which hangs a leaf-and-blossom sprig. Above Q and on the same stem is a similar bulb-like flower, R, with a blossom-and-leaf stem springing upward from it. Between Q and R and on the same stem are 40 various small star-shaped flower forms b c d, and scattered leaf-groups e.

The whole design presents the appearance of being closely worked together, so that no blank fields are left, only so much of the ground 45 appearing between the various forms that constitute the design to enable the end of one figure to be distinguished from the beginning of the next adjacent figure.

The prominent characteristics of the figures 50 of this design are the serrated flowers and the small-lobed leaves.

I claim—

The design for carpets, consisting of the figures A B C D E F G H K L M N O P Q R 55 a b c d e and connected parts, substantially as shown.

WINTHROP L. JACOBS.
